UNITED STATES PATENT OFFICE

EDWARD T. CONDON, OF NEW YORK, N. Y.

DESIGN FOR A COMBINED LIGHTING, SIGNALING AND INDICATING ACCESSORY FOR MOTOR VEHICLES

Application filed November 12, 1931. Serial No. 41,701. Term of patent 14 years.

To all whom it may concern:

Be it known that I, EDWARD T. CONDON, a citizen of the United States, residing at New York, in the county of New York and State of New York, have invented a new, original, and ornamental Design for a Combined Lighting, Signaling, and Indicating Accessory for Motor Vehicles, of which the following is a specification, reference being had to the accompanying drawings, forming part thereof.

Fig. 1 is a front elevation of a combined lighting, signaling and indicating accessory for motor vehicles, showing my new design.

Fig. 2 is a plan thereof.

Fig. 3 is a rear perspective.

I claim:

The ornamental design for a combined lighting, signaling and indicating accessory for motor vehicles, as shown.

EDWARD T. CONDON.
